DISPENSING DEVICE

Mario Calderara, Chatou, France

Application August 9, 1932, Serial No. 628,101
In Belgium August 29, 1931

2 Claims. (Cl. 206—56)

This invention relates to dispensing devices designed primarily for holding creams, semi-liquid or liquid products, such as grease, polish, glue, varnish, oil colors, toothpastes, shaving and 5 toilet creams, medicaments, etc.

One of the objects of the invention is to provide a container collapsible in the direction of its length whereby, when pressure is exerted against one end thereof by any means provided for that purpose, a portion of the contents will be expelled through an orifice provided in the opposite end.

A further object is to provide novel forms of holders for the container whereby it can be used 15 as a refill for the hollow handles of shaving brushes, for cream dispensers and for toothpaste holders or the like.

A still further object is to construct the container in a new and novel manner whereby protection can be effected at low cost and the efficiency of the container as a collapsible structure 20 is increased.

Another object is to provide simple and efficient means for collapsing the container for the 25 purpose of ejecting its contents in desired quantities.

A still further object is to provide a container the bottom of which is assembled therewith in a simple but durable manner whereby the seam 30 formed at the juncture of the parts will resist normal strains to which the container is subjected while it is being filled or collapsed.

A still further object is to provide a container which, initially, is in a collapsed condition but 35 which is expanded by the forceful injection of bulk material thereinto through the orifice provided at the outlet.

With the foregoing and other objects in view which will appear as the description proceeds, the 40 invention resides in the combination and arrangement of parts and in the details of construction hereinafter described and claimed, it being understood that changes in the precise embodiment of the invention herein disclosed may be 45 made within the scope of what is claimed without departing from the spirit of the invention.

In the accompanying drawings the preferred 45 forms of the invention have been shown.

In said drawings:

50 Figure 1 is a section through a shaving brush in which is arranged a container such as embodied in the present invention, said container being used as a refill.

55 Figure 2 is an elevation of the container, a portion being broken away, said container being

shown in the condition in which it is supplied to the trade.

Figure 3 is a perspective view of the thread lining constituting a portion of the feed mechanism of the brush structure shown in Figure 1.

Figure 4 is a perspective view of the guide sleeve used in connection therewith.

Figure 5 is a section through the body member of the holder forming a part of the brush structure, said section being taken on the line 10 5—5, Figure 1.

Figure 6 is a view partly in section and partly in elevation showing the cooperating portions of the body and the cap portions of the holder, said parts being shown separated.

Figure 7 is a bottom plan view of the cap portion of the holder.

Figure 8 is a section similar to Figure 1 showing a modified form of the structure.

Figure 9 is a section through one end portion 20 of another modified form of holder.

Figures 10, 11 and 12 show further modifications.

Figure 13 shows in collapsed condition the modified form of container illustrated in Figure 8.

Figure 14 is a section through the bottom portion of another modified construction of the container.

Figures 15, 16 and 17 are sections through another form of the device.

Referring to the figures by characters of reference, 1 designates a container formed of a tube of thin ductile metal, the bottom portion of which is produced by folding one edge of the tube inwardly, as at 2, to lap an annular flange 3 formed on a disk-like member 4. After these parts have been assembled, as described, the space beneath the member 4 and that surrounded by the portions 2 and 3 is partly or entirely filled with a material 5 formed of metal fabric, plastic, or 40 any other suitable material.

The tubular portion of the container is formed with a continuous thread formed therein by rolling or in any other manner found desirable, this thread being indicated at 6. By extending the 45 threads spirally along the container the tube can be corrugated more readily than would otherwise be possible and at the same time it is rendered collapsible in the direction of its length somewhat after the manner of an accordion.

The top of the container is formed with a screw-threaded neck 7 which normally is engaged by a cap 8 for sealing the contents of the container.

While it has been found practical to form the container as shown in Figures 1 and 2 as has 55

already been described, it is to be understood that if preferred the bottom of the container can be in the form of an inverted cup 9, as shown in Figures 8 and 13, the free edge portion of this cup being gripped within the bottom fold 10 of the corrugated tube 11 and said parts being bound together tightly by an inverted disk 12.

A further modification has been shown in Figure 14 wherein the edge portion of the container 13 is not folded but, instead, is clamped upon an inverted bottom disk 14 by a band or ring 15.

All of the containers herein described are formed with the spiral or thread-like corrugations and all of them are initially produced in a collapsed form, as shown, for example, in Figure 13 wherein the corrugations are substantially flattened on one another and the cup-like portion 9 of the bottom extends close to the neck 7. After a container has been formed in this shape the matter to be held thereby is forcibly injected into the container through the opening in the neck and will act to press against the bottom of the container 1, acting somewhat like a piston, stretch the tube and open out the convolutions substantially as shown in Figures 2 and 8. Caps can then be applied and the containers can be sold to customers for use in dispensing the contents with or without separate holders provided therefor.

While the contents of one of these containers can be ejected by removing cap 8 and pressing the bottom of the container toward the neck, thereby collapsing the container longitudinally, a special advantage is found in the fact that this type of container is especially adapted for use in connection with different kinds of holders. For example, such a container can be used as a refill for a holder in the form of a shaving brush handle, one form of which has been illustrated in Figure 1.

Referring to the Figure 1, 16 constitutes a tubular body portion closed at one end, as shown at 17, while its other end is open and is reduced annularly to provide a neck 18 the base of which is surrounded by a shoulder 19. On this neck are angular lugs 20 oppositely disposed and preferably formed with parallel inclined ends, as shown at 21. Formed on the bottom 17 within the handle is a boss 22 having lugs 23 on the periphery thereof which are regularly spaced.

Removably seated in the body portion 16 is a sleeve 24 in which is rolled or otherwise produced, a screw thread 25. Each end of this sleeve is formed with regularly spaced notches 26 and when the sleeve is seated in the body portion 16 it fits snugly against the inner surface thereof.

A cap 27 is adapted to receive the neck 18 and has an interior annular groove 28 to which lead outlet slots 29 preferably inclined to correspond with the pitch of the ends of lugs 20. Thus cap 27 can be placed over the neck 18 until the lugs 20 reach the slots 29 at which time, by rotating the cap, the lugs will be caused to enter the slots 29, thereby drawing the cap 27 toward shoulder 19. Lugs 20 will ultimately enter groove 28 so that it thus becomes possible to rotate the cap relative to the body 16 without detaching it.

A cap 27 is formed with a central nozzle 30 surrounded by the bristles 31 of a brush, these bristles being held to the cap by any suitable means.

The bore 31 in the nozzle is counterbored at 32 so as to receive the threaded neck 7 of container 1.

Regularly spaced lugs 33 are provided in the cap where they will engage in the notches 26 in one end of the sleeve 24 so that the cap and sleeve 75 can thus rotate together, it being understood that

the bottom end of the sleeve containing notches 26 will be free to move past the lugs 23. Embracing lugs 23 is a notched end 34 of a guide sleeve 35 which is extended around boss 22 and within sleeve 24. Both ends of this sleeve are notched so that the sleeve can be reversed when desired. Obviously the lugs 23 will hold guide sleeve 35 anchored to the body portion 16 while at the same time lugs 33 will engage the threaded sleeve 25 so that it can rotate with cap 27.

Sleeve 35 has a desired number of longitudinal slots 36 and extending slidably within these slots are portions of a head 37 which is slidable in guide sleeve 35 and constitutes a seat for the bottom of the container 1. These projecting portions of the head or follower 37 are joined to a screw-threaded ring which extends around and is slidable on guide sleeve 35 but is in screw-threaded engagement with the inner surface of the threaded sleeve 24.

Normally the head or follower 37 is located at one end of the slots 36 and ring 38 is similarly located. A refill tube or container 1 is inserted into the sleeve 35 so as to rest on the head or follower 37. This refill tube is first joined to cap 27 by screwing its neck into the counterbore 32. Cap 27 is placed upon and joined to the neck 18 as heretofore explained and lugs 33 will become seated in notches 34 at the upper end of sleeve 35.

When it is desired to dispense a portion of the contents of the refill tube or container 1, the cap 27 is rotated relative to the body portion 16. As the threaded sleeve 24 rotates with the cap and as the sleeve 35 and threaded ring 38 are held against rotation by the body portion 16, it will be obvious that this relative rotation of the cap and body portion will cause the ring 38 and the follower 37 to feed longitudinally of the holder, the follower pressing against the bottom of the refill tube or container and collapsing said tube slightly so as to expel a portion of its contents 40 from nozzle 30 into the spaces between the brush bristles.

After all of the contents of the refill tube or container have been expelled the cap is detached from the body portion, the empty tube which is left with the cap is detached therefrom, and the guide sleeve 35 and the threaded sleeve 24 are bodily removed, inverted and reinserted into the body 16, thus bringing the follower 37, which had previously been elevated, into its lowermost position within the body portion. A new refill tube or container is then attached to the cap and is lowered into the sleeve 35 while cap 27 is applied. The structure is then ready for further use.

Another form of brush has been illustrated in Figure 8. In that structure a longitudinally slotted guide sleeve 39 connects a cap 40 with a base 41, there being threaded rings 42 secured to the ends of the sleeve and screwed into the cap and base. The brush 43 is connected to a plug 44 which is screwed into the cap 40 and is adapted to be engaged detachably by the neck 7 of the container. This container is suspended within guide sleeve 39 and rests on a follower 45 which slides in the slots in guide sleeve 39 and is joined to a screw-threaded ring 46 surrounding the guide sleeve.

The body portion 47 of this device has a screw-threaded lining or sleeve 48 which is engaged by the ring 46. Thus by rotating the body portion 47 ring 46 will be shifted longitudinally to collapse the container as heretofore explained.

If cold cream or the like is to be dispensed and it should be desired to deliver the matter into a

bowl-like container, a structure such as illustrated in Figure 9 could be used. Instead of providing the cap 49 with a brush it is formed with a recessed end 50 into which the matter delivered from the container will be discharged. This receiver formed by recess 50 can be covered or protected by a detachable lid 51.

Simplified dispensing means have been illustrated in Figures 10, 11 and 12.

10 In Figure 11, for example, the collapsible container is inserted into a longitudinally slotted guide sleeve 52 closed at one end while its other end has a detachable cap 53 carrying a nozzle 54. The neck of the container is detachably engaged with this cap so as to deliver material to the nozzle and a cover 55 is pivotally attached to the cap, as shown at 56 so as to house the nozzle. A spring 57 bears against angular faces 58 on the cover near its pivot and serves to hold said cover in either closed or open position. By means of a finger piece 59 extending from the cover it can be swung to either of said positions by the thumb or a finger of the hand grasping sleeve 52. Follower 59 is slidable in this sleeve and is connected to an arcuate ring 60 which is slidable on the sleeve 52.

Instead of using a sliding ring the follower 61 can be actuated by a plunger 62 slidable in a longitudinally slotted sleeve 63 as shown in Fig. 10.

30 This plunger is joined to a spring restrained dog 64 the free end of which is adapted to engage the inner surface of sleeve 63. By pressing inwardly on the plunger the dog will shift into or frictionally engage the wall of sleeve 63 and advance follower 61 so that it will press against the housed container 1 which is supported by the cap 65 detachably mounted on sleeve 63. Intermittent thrusts against plunger 62 will feed the follower intermittently against the container to collapse it 40 and the pull exerted by spring 66 on dog 64 will be sufficient to maintain the follower in any position to which it may be moved.

In Figure 12 there has been shown a holder in the form of a sleeve 67 formed of a spirally wound band spring one end of which is attached to a cap 68 while the other end is detachably joined to a head 69. A container supported by cap 68 can be collapsed in the direction of its length by contacting the sleeve 67 longitudinally.

Obviously, various other modifications can be made within the scope of the present invention. For example, and as shown in Figures 15, 16 and 17, an ordinary collapsible tube T can be compressed by a grooved spherical roller 70 advanced intermittently by a pawl and ratchet mechanism 71 operated by a spring restrained plunger 72 slidable along a slot 73 in the casing 74 in which the tube is retained by a cap 75.

What is claimed is:

1. A container comprising, in combination, a spirally corrugated tube made of a plastic material provided at one end with an outlet nozzle, a hollow cup-shaped end piece extending inwardly in said tube to a distance substantially equal to the length of said tube when all the corrugations thereof have been flattened against one another, with the edge of said tube being folded about the edge of said end-piece, and a disc fitting in said end piece so as to tightly hold the edge of said tube between the periphery of said disc and the edge of said end piece. 20

2. A container comprising, in combination, a spirally corrugated tube made of a plastic material provided at one end with an outlet nozzle, a hollow cup-shaped end piece extending inwardly in said tube to a distance substantially equal to the length of said tube when all the corrugations thereof have been flattened against one another, and a disc having a cylindrical flange fitting in said end piece so as to tightly hold the edge of said tube between the periphery of said disc and the edge or flange of said end piece. 30 35 40
